UNITED STATES PATENT OFFICE.

ROBERT E. TAYLOR AND WILLIAM A. TAYLOR, OF BROWNSVILLE, TENN.

FENCE.

SPECIFICATION forming part of Letters Patent No. 276,095, dated April 17, 1883.

Application filed January 16, 1883. (No model.)

To all whom it may concern:

Be it known that we, ROBERT E. TAYLOR and WILLIAM A. TAYLOR, of Brownsville, in the county of Haywood and State of Tennessee, have invented certain new and useful Improvements in Fences; and we do hereby declare that the following is a full, clear, and exact description of the invention, which will enable others skilled in the art to which it applies to make and use the same, reference being had to the accompanying drawings, which form a part of this specification, and in which—

Figure 1 is a perspective view of our improved fence. Fig. 2 is a top view of the same; and Fig. 3 is a vertical section on line $x x$, Fig. 2.

Similar letters of reference indicate corresponding parts in all the figures.

Our invention has relation to fences; and it consists in the improved construction and combination of parts of a worm-fence, as herein-after more fully described and claimed.

In the accompanying drawings, the letter A indicates a board or plank nailed or otherwise fastened to the upper parts of the posts B, which are driven into the ground alternately on both sides of the plank. Above this plank may be fastened a barbed wire, C, to prevent persons and animals from passing over the fence. Under the plank is built a worm-fence, of rails D, in the usual manner, supported by the posts B and by smaller posts E, which clamp the crossed ends of the rails. The ends of the rails are crossed upon the outer side of the posts B—*i. e.*, the side which faces away

from the plank A—and the ends of the outer posts, E, are held fast and prevented from sagging by wire loops F, fastened to the posts B by means of screw-eyes G, and passed over 40 the end of the posts E. These screw-eyes G consist of eyes H, having screw-threaded shanks I, which pass through holes in posts B, and are secured by nuts J upon the other side of the posts. By tightening the nut upon 45 the shank the loop is drawn closer to the post and the post E with it, clasping the crossed ends of the rails and holding them fast.

By this construction of a fence a strong and easily-constructed fence is provided, the plank 50 and posts keeping the different panels firmly together, while the position of the rails forming a worm-fence produces a wider base for the fence, increasing its power of resistance.

Having thus described our invention, we 55 claim and desire to secure by Letters Patent of the United States—

The herein-described fence, consisting of the plank A, posts B, placed alternately on both sides of plank A, and provided with screw-eyes G and wireloops F, posts E, and rails D, the whole constructed and combined substantially as and for the purpose shown and set forth.

In testimony that we claim the foregoing as 65 our own we have hereunto affixed our signatures in presence of two witnesses.

ROBERT EDWIN TAYLOR.

WILLIAM ALEXANDER TAYLOR.
